CLAIM

The ornamental design for a messenger bag, as shown and described.

DESCRIPTION

FIG. 1 is a front perspective view of a messenger bag showing the claimed design;
 FIG. 2 is a front elevational view thereof;
 FIG. 3 is a rear elevational view thereof;
 FIG. 4 is a right side elevational view thereof;
 FIG. 5 is a left side elevational thereof;
 FIG. 6 is a top plan view thereof; and,
 FIG. 7 is a bottom plan view thereof.

The broken lines in the figures show portions of the messenger bag that form no part of the claimed design.
